IRONING MACHINE

Herbert C. Bowen, Detroit, Mich., assignor to
 Hydraulic Brake Company, Detroit, Mich., a
 corporation of California

Application May 19, 1934, Serial No. 726,602

13 Claims. (Cl. 38—25)

This invention relates to ironing machines.

Broadly the invention comprehends an ironing machine including cooperating ironing elements, fluid pressure means for actuating one of the ironing elements to create an ironing pressure between the elements, and means for automatically creating an initial pressure in the fluid pressure means by movement of the other ironing element into operative position.

10 The illustrated embodiment of the invention discloses cooperative ironing elements, a fluid pressure system including a fluid reservoir, a fluid pressure producing device supplied therefrom, expansible elements connected to the device for actuating one of the elements, and pressure producing means in the reservoir operably connected to the other ironing element and actuated thereby upon movement thereof into operative position to introduce an initial pressure in the system.

20 An object of the invention is to provide an ironing machine including cooperative ironing elements, one actuated by fluid pressure means including means for creating an initial pressure in the system to move the element so as to compensate for variations in the thickness of the material or article upon which work is to be performed.

Another object of the invention is to provide 30 an ironing machine including cooperative ironing elements and a fluid pressure means for actuating one of the elements including means for creating an initial pressure in the system upon movement of the other element into operative position.

35 A feature of the invention is a pair of cooperative ironing elements and a fluid pressure system for actuating one of the elements including a reservoir, a piston movable in the reservoir for creating an initial pressure in the system, a pressure producing element supplied from the reservoir, and expansible elements connected to the pressure producing element, and a valve associated with the pressure producing element for 45 relieving pressure in the system.

Another feature of the invention is a pair of 50 cooperative ironing elements one actuated by a fluid pressure system and the other attached to a movable support arranged to swing the element into and from operative position, means for automatically locking the support upon movement of the ironing element into operative position, and means for tripping the locking means operable automatically upon release of pressure in the 55 fluid pressure system.

Other objects and features of the invention will appear from the following description taken in connection with the drawings forming a part of this specification, and in which,—

Figure 1 is a cross-sectional view of an ironing machine embodying the invention;

Figure 2 is a fragmentary view illustrating the actuating means for the head of the machine;

Figure 3 is a fragmentary view illustrating the linkage between the head and the actuating means for the head;

Figure 4 is an enlarged detail view substantially on line 4—4, Figure 2;

Figure 5 is a sectional view substantially on line 5—5, Figure 1;

Figure 6 is a side elevation substantially on line 6—6, Figure 5;

Figure 7 is a top plan view of the buck support;

Figure 8 is a side elevation, partly in section and partly broken away, illustrating the assembly of the fluid pressure means, the buck support, and the buck;

Figure 9 is an enlarged sectional view of one of the motors and guides for the buck;

Figure 10 is a top plan view of the fluid pressure producing device;

Figure 11 is a side elevation of the fluid pressure producing device partly in section;

Figure 12 is a sectional view substantially on line 12—12, Figure 11;

Figure 13 is a sectional view substantially on line 13—13, Figure 10; and

Figure 14 is a diagrammatical illustration of the electrical circuit for the machine.

Referring to the drawings, 10 represents a frame including a casting having a sump 12 at one end and a hollow vertical column 14 at its other end. A sleeve 16, bolted or otherwise secured to the frame concentrically to the column 14, has fitted therein a column 18 providing the main support for the frame, and secured to the frame are corresponding legs 20 for cooperation with the main support or column 18. It is to be understood that other desirable means for supporting the frame may be employed.

A top 22 supported on the frame has an opening for the reception of the column 14, and a frusto-conical portion 24 extending upwardly immediately above the sump 12, and the frusto-conical portion has an opening in its top, the object of which will hereinafter appear. The top also has the conventional apron 26 concealing the frame.

A fluid pressure producing device 28 is suitably mounted in the sump 12. This device includes a casting comprising a reservoir 30 closed at its top as by a plug 32 having therein a two-way valve 5 34 controlling vents 36 to the atmosphere. Formed on the outer wall of the reservoir adjacent the top thereof are flanges 38, providing a suitable mounting for a buck support to be hereinafter described, and formed in the wall of the 10 reservoir is a passage 40, the purpose of which will hereinafter appear.

A reciprocal piston 42 in the reservoir has a rod 44 extending downward through a bore 46 and a packing box 48 in the outer end of the bore, and 15 attached to the rod is a clevis 50. The piston has a plurality of openings 52 providing communications between the respective ends of the reservoir, and positioned on the piston is a collapsible leak-proof cup 54 held against displacement by a 20 spring 56 interposed between the cup and the bottom of the reservoir.

Spaced parallel cylinders 58 and 60 are formed in the base of the casting normal to the reservoir. The cylinder 58 has an inlet port 62 communicating 25 with the reservoir, and a discharge port 64 communicating with a valve chamber 66 having therein a check valve 68 for control of a discharge port 70. A reciprocal piston 72 in the cylinder 58 has a reduced body portion providing in 30 conjunction with the wall of the cylinder an annular chamber 74 communicating by way of the port 62 with the reservoir. The head of the piston has a plurality of ports 76 providing communication between the chamber 74 and that 35 portion of the cylinder forward of the piston, and a concentric extension 78.

A leak-proof cup 80, adapted to seat on the head of the piston and close the port 76 during the compression stroke of the piston, has a concentric opening receiving the extension 78 with substantial clearance as indicated at 82, so that upon the retracted stroke of the piston fluid may pass from the reservoir to the chamber 74, and thence through the port 76 past the cup 80 to 45 that portion of the cylinder chamber forward of the piston. The cup is retained against displacement by a perforated disk 84 held on the extension 78 by a spring 86 interposed between the disk and the head of the cylinder. This spring 50 also serves to return the piston to its retracted position. In the back of the piston is a recess 88, and fitted in the recess is a sleeve 90 having a radial flange 92 adapted to seat on a ring 94 fitted in a circumferential groove in the wall of 55 the cylinder, and a leak-proof cup 96 is clamped between the flange and the piston.

A shaft 98 journaled in a bearing 100 on the frame has secured thereto an adjustable operating lever 102 limited in its throw by adjustable stops 104 and 106, and adjustably attached to the lever 102 is an operating handle 108. The shaft has suitably secured thereto a cross-lever 110, and a thrust pin 112 pivoted to one end of the lever 110 is received by the recess 88 in the back 60 of the piston, and the lever 110 has an off-set bifurcated portion 114, the purpose of which will hereinafter appear.

The cylinder 60 has a diaphragm 116 dividing the cylinder into two compartments 118 and 120, and the diaphragm has a port 122 providing a communication between the compartments. The compartment 120 is closed as by a plug 124 and is provided with a port 126. A leak-proof cup 128 seated on the diaphragm within the compartment 120 has an opening 130 of smaller diameter 75

than the ports 122, and the cup is held against displacement by a spring 132 interposed between the cup and the plug.

The compartment 118 has a port 134 providing a communication between the compartment and the reservoir, and the compartment is closed as by a plug 136 having a chamber 138 in its outer end. A valve 140 in the compartment has a stem 142 extending through the plug 136 and the chamber 138. A leak-proof cup 144 is seated on the plug and held against displacement by a relatively light spring 146 interposed between the cup and a flange on the head of the valve. The head of the valve has a reduced concentrical portion 148 adapted to abut the diaphragm 116 and an extension 150 adapted to enter the port 122 and to engage the periphery defining the opening in the cup 128 so as to completely seal the port 122.

The stem 142 of the valve 140 extends through a cap 152 threaded in the open end of the chamber 138, and fitted on the stem within the chamber is a collar 154, and a spring 156 sleeved on the stem 142 between the cap 152 and the collar 154 urges the valve 140 to its seat on the diaphragm. The rate of movement of the valve is dependent upon the tension on the spring 156. This may be regulated by adjusting the cap 152. The stem is further provided with spaced collars, between which is positioned the bifurcated portion 114 on the lever 110.

A buck support 158 is bolted or otherwise secured to the flange 38 on the reservoir of the pressure producing unit 28. This support includes an elongated receptacle having its edges rolled to lend strength and rigidity to the structure. 35 As shown, the bottom of the receptacle is swedged as indicated at 160, and the swedged portion is provided with an opening for the reception of the upper end of the reservoir. Because of the swedged portion 160, the receptacle is lowered to 40 substantially close the space between the bottom of the receptacle and the frusto-conical portion 24 on the top 22.

Corresponding motor cylinders 162 and 164 are suitably mounted in the respective ends of the 45 receptacle or buck support, and formed on the wall of the respective cylinders are oppositely disposed guides 166 and 168. The cylinder 162 is connected by a conduit 170 to a fitting 172, the cylinder 164 is connected by a conduit 174 to the fitting 172, and the fitting 172 is connected by conduits 176 and 178, respectively, to the port 126 in the compartment 120 and the port 70 of the chamber 66.

A fluid pressure switch 180 is connected to 55 the fitting 172. This switch is connected in a circuit 182 having a lamp 184 connected therein. The circuit 182 is tapped off of a circuit 186 having connected therein a heating element 188 and a rheostat 190. The circuit 182 is adaptable 60 for connection to a suitable source of electrical supply.

Each of the motor cylinders has therein a reciprocal piston 192. The head of the piston has an extension 194 adapted to support the piston 65 in spaced relation to the head of the cylinder so that fluid upon entering the cylinder will be properly received by the piston. A leak-proof cup 196 on the head of the piston is retained against displacement by the extension 194 and 70 an axial port through the piston is closed by a bleeder screw 198, and a cap 200 fitted on the back of the piston protects the bleeder screw.

A buck 202 has dependent pins 204 received by the guides 166 and 168, and pressure blocks 75

206 adapted to engage the caps 200 on the respective piston 192. The buck has thereon a suitable padding 208 and a fabric cover 210.

The column 14 has a semi-spherical top 212 having therein oppositely disposed bosses 214 bored for the reception of a pintle 216 on which is pivotally mounted a hollow arm 218 having a portion adapted to telescope the semi-spherical portion 212 on the column.

10 The arm has oppositely disposed horns 220 to which is attached a head 222 adaptable for cooperation with the buck 202. The arm 218 houses the electrical circuits 182 and 186; the lamp 184 in the circuit 182 is positioned in the arm centrally between the horns and immediately back of an opening having therein a colored glass insert 224 through which the light rays from the lamp may be projected; the heating element 188 and the rheostat 190 are encased in the head, 15 and suitably secured to the arm between the horns is a rod 226 having on its free end a hand grip or knob 228 by means of which the head may be lowered into operative position.

The arm 218 has an internal web 230 supporting an extension 232 of the arm. The free end of this extension projects into the column 14 and has secured thereto a case-hardened block 234, and formed in the extension 232 eccentrically to the pintle is a notch 236. A lever 238 pivoted 25 on the frame has on one end a segment 240 on which the extension 232 rides as the head is moved into and from operative position, and this end of the lever is adapted to engage the block 234 on the extension when the head is moved into operative position. The other end of the lever 238 is arranged to engage a notch in the cross lever 110, and a rod 242 connects the lever 110 to the lever 238 eccentrically of its fulcrum, and a spring 244 is connected between 30 the lever 238 and the frame.

A lever 246 fulcrumed on the frame is connected by a link 248 to the extension 232 of the arm 218. As shown, the link 248 is received by the notch 236 in the extension 232, and the lever 246 is connected by springs 250 to a bracket 252 on the sump 12, and by a spring 254 to one leg of a bell crank lever 256 fulcrumed on a bracket 258 on the sump 12, and the other leg of the bell crank lever 256 is connected to the clevis 50 35 on the rod 44 of the piston 52 in the reservoir 30.

Assuming that the fluid pressure system is filled with liquid, that the circuit 186 is connected to a suitable source of electrical supply, and that the head 222 of the machine is in elevated position, under these circumstances, the operator places the work upon the buck 202 and lowers the head into operative position. As the head is lowered into operative position the extension 232 of the arm 218 travels on the segment 240, 40 and when the head assumes the operative position the lever 238 engages the block 234 carried by the arm and effectively locks the head against movement.

This movement of the head is transmitted 45 through the link 248 to the lever 246 to swing this lever on its pivot and this movement of lever 246 is transmitted through spring 254 to bell crank lever 256 and rod 44 to the piston 42 in the reservoir to move the piston on its compression stroke. Upon the initial movement of the piston 42 the cup 54 carried thereby closes the lower end of the passage 40, and upon further movement of the piston the fluid in the reservoir is displaced through the port 62 into 50 the chamber 74, thence through ports 76, past

cup 80 into the cylinder 58 forward of the piston 72, thence through port 64 into chamber 66 past the valve 68 and through conduit 178, coupling 172 and conduits 170 and 174 into the motor cylinders 162 and 164, resulting in actuation of the pistons 192 to raise the buck into engagement with the head. The distance travelled by the buck during this operation is dependent upon the thickness of the work, and to compensate for variations in the thickness of the work variation in the fluid pressure means is obtained by the introduction of the spring 254 in the linkage for actuating the fluid pressure means by movement of the head into operative position. 15

After the above described operation, the operator depresses the lever 102 to rock the shaft 98, and this movement of the shaft is transmitted by the arm 110 on the shaft and thrust pin 112 connected thereto to the piston 12 to move the piston 72 on its compression stroke. As the piston 72 moves on its compression stroke, the fluid in the cylinder 58 is displaced through port 64 into valve chamber 66, past the valve 68, thence through port 70, conduit 178, coupling 172 and conduits 170 and 174 into the motor cylinders 162 and 164, resulting in actuation of the pistons 192 and movement thereby of the buck 202 against the head with sufficient pressure to effectively iron the work. Upon attaining the desired pressure in the system, the fluid pressure switch 180 is actuated to close the circuit 182 and light the lamp 184 so that the operator may have a visual indication that adequate pressure is applied. 25

After completing the above described operations the operator manipulates the lever 102 to rock the shaft 98, and this movement of the shaft is transmitted to the arm 110 carried by the shaft and the thrust pin 112 connected to the arm to 30 release the force applied to the piston 12, whereupon the check valve 68 closes and the piston is returned to its retracted position under the influence of spring 86. As the piston returns to its retracted position fluid is drawn from the reservoir 30, through port 62 into the chamber 74, thence through port 76, past the cup 80 into the cylinder 58 forward of the head of the piston to fill the chamber for a subsequent operation. 35

After relieving the applied force on the piston 50 the arm 110 trips the valve 140 and opens the port 122, resulting in relieving pressure in the motor cylinders 162 and 164, followed by the return of the buck 202 to its normal position. Upon opening the port 122, the fluid is returned from the 55 motor cylinders 162 and 164 through the conduits 170 and 174 to the coupling 172 and conduit 176 to the valve chamber, and thence through port 134 to the reservoir.

Further movement of the shaft in the same direction is transmitted through the arm 110 and rod 242 to the lever 238 to disengage this lever from the extension 232 on the arm 218 and to engage the lever with the arm 110 to lock the arm 110 against movement so that the fluid pressure system cannot be operated. 60

Upon disengaging the lever 238 from the extension of arm 218, the springs 250 function to rock the bell crank lever 246, and this movement of the bell crank lever is transmitted through the link 248 to the arm 218 to swing the head into elevated position. During this movement tension on the spring 254 is released, whereupon the spring 86 returns the piston 42 in the reservoir 30 70 to its normal position. As the piston 42 returns 75

to its normal position the cup 54 thereon collapses and fluid flows from the reservoir back of the piston through the ports 52, past the cup 54 into that portion of the reservoir forward of the piston, and when the piston is fully returned to its normal position the passage 40 is open so as to equalize the pressure of the fluid in the reservoir.

Although this invention has been described in connection with certain specific embodiments, the principles involved are susceptible of numerous other applications that will readily occur to persons skilled in the art. The invention is, therefore, to be limited only as indicated by the scope 15 of the appended claims.

I claim:-

1. An ironing machine comprising relatively movable ironing elements, a fluid pressure system for actuating one of the elements including means 20 for producing pressure in the system, a member supporting the other element for movement into and from operative position, and means connecting the member to the pressure producing means for actuating the pressure producing means upon 25 movement of the member to place the last mentioned element into operative position.

2. An ironing machine comprising relatively movable ironing elements, a fluid pressure system for actuating one of the elements including means 30 for producing an initial pressure in the system and means for producing a greater pressure in the system, a pivoted member supporting the other element for movement into and from operative position, means connecting the pivoted member to the means for producing an initial pressure for 35 operation by movement of the pivoted member to create the initial pressure and manually operated means for actuating the means for producing the greater pressure in the system.

40 3. An ironing machine comprising relatively movable ironing elements, a fluid pressure system for actuating one of the ironing elements including fluid pressure motors operatively connected to the element and a fluid pressure device for 45 delivering fluid under pressure to the motors, and means for actuating the device by movement of the other ironing element into operative position.

4. An ironing machine comprising relatively 50 movable ironing elements, a fluid pressure system for actuating one of the ironing elements including a fluid pressure device and expansible elements operatively connected thereto and to one of the ironing elements, manually operated means 55 for actuating the fluid pressure device, manually operated means for actuating the other ironing element, means for alternatively locking the actuating means for the fluid pressure device and the last mentioned ironing element, and means for 60 actuating the fluid pressure device by movement of the manually operated ironing element into operative position.

5. An ironing machine comprising a pair of relatively movable ironing elements, a fluid pressure system for actuating one of the elements including means for producing an initial pressure in the system, means connecting the means for producing the initial pressure to the other element for operation by movement of the last- 70 mentioned element to create the initial pressure, and means for operating the system to create an ironing pressure between the elements.

6. An ironing machine comprising a head, means for moving the head into and from operative position, means for locking the head in oper-

ative position, a movable buck cooperating with the head, expansible means for moving the buck to create an ironing pressure between the head and the buck, a pressure producing means for supplying fluid under pressure to the expansible means, and means operable by movement of the head into operative position for actuating the pressure producing means to create an initial pressure in the expansible means, and manually operated means for actuating the pressure producing means.

7. An ironing machine comprising a head, a buck for cooperation therewith, a movable support for swinging the head into and from operative position, means for locking the head in operative position, a fluid pressure system for actuating the buck, a reservoir for supplying fluid to the system, means in the reservoir for creating pressure on the fluid therein, and means connecting the movable support to the means in the reservoir for creating pressure on the fluid so as to introduce an initial pressure in the system upon movement of the head into operative position.

8. An ironing machine comprising a head, a buck for cooperation therewith, a movable support for swinging the head into and from operative position, means cooperating with the support for locking the head in operative position, a fluid pressure system for actuating the buck including a reservoir for supplying fluid to the system, a piston in the reservoir for imposing pressure on the fluid therein, and linkage connecting the movable support to the piston for moving the piston on its compression stroke to introduce an initial pressure in the system upon swinging the head into operative position.

9. An ironing machine comprising a head, a buck for cooperation therewith, a movable support for swinging the head into and from operative position, a fluid pressure system for actuating the buck including a pressure producing device, fluid pressure motors connected to the device and operatively connected to the buck, actuating means for the device, and a lever engaging the movable support and the actuating means for the device 45 operable to alternatively lock the support and the actuating means for the device against movement.

10. An ironing machine comprising a head, a buck for cooperation therewith, a movable support for swinging the head into and from operative position, a fluid pressure system for actuating the buck including a fluid reservoir, a fluid pressure device receiving fluid from the reservoir, fluid pressure actuated motors connected to the device and operatively connected to the buck, 55 means for actuating the device, a piston in the reservoir for imposing pressure on the fluid therein, linkage connecting the movable support to the piston for moving the piston on its compression stroke upon movement of the head into operative 60 position, a lever adapted to alternatively engage the movable support and the actuating means for the device for alternatively locking the support and the actuating means for the device against movement.

11. An ironing machine comprising a head, a buck for cooperation therewith, a movable support for moving the head into and from operative position, a fluid pressure system for actuating the buck including a reservoir, a pressure-producing device receiving fluid from the reservoir, fluid pressure operated motors connected to the pressure producing device and operatively connected to the buck, and means for actuating the pressure-producing device, a piston in the reser- 75

- voir for creating pressure on the fluid therein, linkage connecting the movable support to the piston for moving the piston on its compression stroke upon movement of the head into operative position, a lever adapted to engage the movable support and the actuating means for the pressure producing device for alternatively locking the support and the actuating means for the pressure producing device.
- 5 12. An ironing machine comprising a head, a buck for cooperation therewith, means supporting the head for movement into and from operative position, a fluid pressure system for actuating the buck including a reservoir, a pressure producing device supplied therefrom, fluid operated motors operatively connected to the buck and to the pressure producing device, a piston in the reservoir, means connecting the piston and head supporting means for concomitant movement, means for actuating the pressure producing device, means for alternatively locking the head supporting means and the actuating means for the pressure producing device, means for automatically actuating the locking means upon movement of the head into operative position to unlock the 10 actuating means for the pressure producing device, means connecting the locking means to the means for actuating the pressure producing device for unlocking the head supporting means, and means effective upon unlocking the head 15 supporting means to return the head to inoperative position.
- 15 20. An ironing machine comprising a head, a
